UNITED STATES PATENT OFFICE.

EDWARD L. MARKLE, OF CHICAGO, ILLINOIS.

CUTTER-GUARD.

1,068,150.

Specification of Letters Patent.

Patented July 22, 1913.

Application filed September 23, 1912. Serial No. 721,850.

To all whom it may concern:

Be it known that I, EDWARD L. MARKLE, a citizen of the United States, residing at Chicago, in the county of Cook and State of Illinois, have invented certain new and useful Improvements in Cutter-Guards, of which the following is a specification.

The guard which is the subject of the present invention is designed more particularly for use in connection with jointers and similar wood-working machines having rotating cutters.

It is the object of the invention to provide a guard of the kind stated which is simple in construction, which can be easily attached to the machine, and which will effectually protect the operator from injury by the cutters. These objects are attained by a novel combination and arrangement of parts to be hereinafter described and claimed, reference being had to the accompanying drawing forming a part of this specification.

In the drawing, Figure 1 is an elevation of the machine showing the application of the invention. Fig. 2 is a plan view of a fragment of the machine showing the position of the guard. Fig. 3 is an end view of the machine. Fig. 4 is a perspective view 30 of the guard removed. Fig. 5 is a horizontal section on the line 5—5 of Fig. 1. Fig. 6 is a vertical section on the line 6—6 of Fig. 1, and Figs. 7 and 8 are horizontal sections on the lines 7—7 and 8—8, respectively, 35 of Fig. 6.

In the drawing, 5 denotes the bed of a jointer or similar wood-working machine having a guide 6 for the work, and a revolving horizontal cutter 7 which latter projects through an opening in the bed, as usual. These as well as the other parts of the machine, are all constructed and arranged in the ordinary way, and as they form no part of the present invention, a detailed description thereof is deemed unnecessary.

In order to protect the hands of the operator from injury by the cutter 7, there is provided a guard comprising an arm 8 having one end enlarged as indicated at 9 so that said enlargement may serve as a cover for the cutter. The other end of the arm has a hub 10 by which it is pivoted on a vertical rod 11. The guard extends horizontally across the bed 5 and its pivotal connection with the rod 11 allows it to swing in a

horizontal plane. The rod 11 is held in a support comprising two members 12 and 13 which are bolted together, as indicated at 14, and between which the rod is adjustably clamped, the contiguous faces of the members having registering grooves in which the rod seats, as shown in Fig. 8. The member 12 has at its lower end a depending stem 15 which is square in cross section and extends through a vertical aperture 16 in the enlarged outer end of a horizontal bracket 17 which latter is bolted or otherwise rigidly secured to one side of the machine frame. The upper end of the member 12 has a reduced portion 18 to accommodate the hub 10, and said part 18 terminates in a lateral projection 19 which overhangs the hub and has a vertical opening to receive the upper end of the rod 11. The member 13 extends only as far as the hub, and the latter is located between the same and the projection 19, and also between the latter and the shoulder formed by the part 18, as shown in Fig. 6. This structure provides a bearing for the ends of the hub and prevents vertical movement thereof on the rod 11.

The inner end of the arm 8 is hollow and in said hollow is a web 20 to which is anchored one end of a coiled spring 21. The other end of the spring is anchored to a projecting flange 22 on the member 12. The function of this spring is to hold the guard swung over against the guide 6, as shown in Fig. 2, in which position it covers the cutter 7.

A guard constructed as herein described effectually serves the purpose for which it is designed. It is simple in construction, and it can be readily attached to the machine.

I claim:

1. The combination of a supporting bracket having an aperture, a rod, a pair of clamping members between which the rod is held, one of said members having a stem which seats in the aforesaid aperture, and a cutter guard having an arm which is pivoted on the rod.

2. The combination of a supporting bracket having an aperture, a rod, a pair of clamping members between which the rod is held, one of said members having a stem which seats in the aforesaid aperture, a cutter guard having an arm which is pivoted on the rod, and a spring connected to the arm for swinging the guard in one direction.

3. The combination of a supporting bracket having an aperture, a rod, a pair of clamping members between which the rod is held, one of said members having at one 5 end a stem which seats in the aforesaid aperture, the other end of said member having a reduced portion terminating in a projecting part having an opening into which the rod extends, and a cutter guard having 10 an arm provided with a hub through which the rod passes, said hub being located between the aforesaid projecting part of one of the clamping members and the other member.
- 15 4. The combination of a supporting bracket having an aperture, a rod, a pair

of clamping members between which the rod is held, one of said members having a stem which seats in the aforesaid aperture, a cutter guard having an arm which is 20 pivoted on the rod, the inner end of the arm being hollow and having a web, and a spring anchored at one end to the web, and at its other end to one of the aforesaid clamping members.

25 In testimony whereof I affix my signature in presence of two witnesses.

EDWARD L. MARKLE.
